UNITED STATES PATENT OFFICE

161,318

COIN SAVINGS BANK

Harry L. Cooper, St. Louis, Mo.

Application August 1, 1949, Serial No. 4,238

Term of patent 7 years

(Cl. D34—11)

To all whom it may concern:

Be it known that I, Harry L. Cooper, a citizen of the United States, residing at the city of St. Louis, State of Missouri, have invented a new, original, and ornamental Design for a Coin Savings Bank, of which the following is a specification, reference being had to the accompanying drawing, forming a part hereof.

Fig. 1 is a front view of a coin savings bank, showing my new design, and

Fig. 2 is a side view of the same.

I claim:

The ornamental design for a coin savings bank, as shown.

HARRY L. COOPER.
